(57) **CLAIM**

The ornamental design for a random orbital polishing tool, as shown and described.

DESCRIPTION

FIG. 1 is a perspective view of a random orbital polishing tool showing the new design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a rear view thereof.

The broken, dashed lines in the drawings are shown for illustrative purposes only and form no part of the claimed design. The dash-dot line in the drawings define a boundary of the claim. The claimed design extends up to, but does not include, the dash-dot line.
